(57) CLAIM

The ornamental design for an e-bike, as shown and described.

DESCRIPTION

FIG. 1 is a front perspective view of an e-bike according to the present invention;

FIG. 2 is a rear perspective view of the e-bike of FIG. 1;

FIG. 3 is a top view of the e-bike of FIG. 1;

FIG. 4 is a bottom view of the e-bike of FIG. 1;

FIG. 5 is a front view of the e-bike of FIG. 1;

FIG. 6 is a rear view of the e-bike of FIG. 1;

FIG. 7 is a left side view of the e-bike of FIG. 1;

FIG. 8 is a right side view of the e-bike of FIG. 1; and,

FIG. 9 is a close-up perspective view of a portion of the e-bike of FIG. 1.

The broken lines represent portions of the e-bike that form no part of the claimed design.
